UNITED STATES PATENT OFFICE

HARRY SEBELL, OF BOSTON, MASSACHUSETTS, ASSIGNOR TO ARTHUR H. PARKER, OF LEXINGTON, MASSACHUSETTS

CAN-SEALING MACHINE

Application filed September 27, 1928. Serial No. 308,658.

This invention relates to can-sealing machines of the type which are adapted to seal a can by assembling a can and cover and applying a U-shaped sealing strip thereto.

5 One of the objects of the present invention is to provide an improved can-sealing machine of the above type which is constructed to utilize separate formed sealing strips in the sealing of the successive cans. A plurality of these separate formed sealing strips may be placed in a magazine from which they are fed separately and individually to the cans as the latter are successively brought into sealing position.

15 Another object of the invention is to provide an improved sealing machine constructed to seal a can of the above-mentioned type in which the sealing flange of the can cover lies within the outlines of the can body. In 20 a can of this type the body is formed with an annular re-entrant portion or groove directly below the sealing flange with the result that the exterior diameter of the sealing flange will be no greater than the diameter 25 of the can.

As stated above one feature of the invention relates to a novel construction by which a can of this type may be sealed with a U-shaped sealing strip.

30 Other objects of the invention are to improve generally can-sealing machines of this type all as will be more fully hereinafter set forth.

In order to give an understanding of the 35 invention I have illustrated in the drawings a selected embodiment thereof which will now be described after which the novel features will be pointed out in the appended claims.

40 Fig. 1 is a side view of a can-sealing machine embodying my invention, with certain parts removed to better show the operation;

Fig. 2 is a top plan view of the machine;

45 Fig. 3 is a view showing the opposite side of the machine from that shown in Fig. 1 and illustrating the strip magazine in section.

Fig. 4 is a section on the line 4—4, Fig. 1;

50 Fig. 5 is an enlarged sectional view of the strip-feeding means for the strip magazine;

Fig. 6 is a view illustrating the feed for the individual strips;

Fig. 7 is an enlarged section on the line 7—7, Fig. 6;

Fig. 8 is an enlarged section on the line 8—8, Fig. 6;

Figs. 9 and 10 are fragmentary-sectional views showing the sealing members, Fig. 9 illustrating the position of the parts when the cover is first inserted into the can and Fig. 10 illustrating the position of the parts during the sealing operation;

Fig. 11 is a section on the line 11—11, Fig. 1;

Fig. 12 is a section on the line 12—12, Fig. 1;

Before describing in detail the machine herein illustrated I will refer briefly to one style of can that may be sealed by means of the machine. As stated above the machine 70 relates particularly to the sealing of cans by means of a U-shaped sealing strip which is designed to embrace a sealing flange on either the can body or the can cover and to be clamped against the other part. In the 75 construction shown the can cover has a sealing flange which is embraced by the U-shaped sealing strip and during the sealing operation the strip is clamped firmly onto the sealing flange and also clamped 80 firmly against some part of the can body which, in the particular shape of can herein illustrated, is a second sealing flange.

In Figs. 9 and 10 I have shown a can comprising a can body 1 and a cover 3 which is formed with an upstanding curb 4 that fits within the mouth of the can and is also formed with a laterally-extending sealing flange 5. The can is sealed through the medium of a U-shaped sealing strip which embraces the sealing flange 5 and is clamped against a portion of the can body which, in the construction shown in Figs. 1 and 2, is a second sealing flange 2 with which the body is provided and which underlies the sealing flange 5 of the cover. The U-shaped sealing strip 6 is clamped tightly to the sealing flanges thereby to form the completed seal.

In the can body herein shown the upper 100

end of the side walls of the can directly below the sealing flange 2 are bent inwardly as shown at 200 to form a portion of smaller diameter than the can body and the sealing flange 2 extends outwardly from the upper end of the portion 200. With this construction there will be formed a groove 201 around the exterior of the can directly beneath the sealing flange 2 and the latter will be located within the outline of the can body. Furthermore, the can cover 3 is shown as formed with a locking flange 7 which overlies the upper side of the sealing strip 6, said locking flange, sealing strip and sealing flange all being 15 pressed firmly together.

I have herein shown my invention as applied to a can-sealing machine having means for automatically feeding can bodies 1 and can covers 3 into position to be assembled.

20 The can bodies 1 are fed into the machine along a runway 8 by any suitable can-feeding means and are delivered into semi-circular holding elements 9 which are mounted on a suitable turret 10. Said turret is given an 25 intermittent rotary movement by which the can bodies are carried around into sealing position. The can covers 3 are also fed into these holders 9 by suitable feeding mechanism.

30 A pile of covers will be stacked in a magazine 11 and the bottom cover of the stack is fed automatically into the U-shaped holding member which occupies the position shown at 9^a in Fig. 2. The holding member is slightly 35 greater than semi-circular so that when each can cover is forced into a holding member it will be frictionally retained therein.

The turret carrying the holding members 9, 9^a, etc. rotates clockwise in Fig. 2 and hence 40 as it rotates each holding member carrying a cover will be brought into the position of the holder 9 and while in such position a can body will be fed into the holder directly beneath the cover. At the next forward movement of the turret the cover and can are carried around into the can-sealing position in which the can body 1 is directly over a table 12 and the can cover is directly under a chuck 13. This mechanism for feeding the 45 can and the cover into sealing position may be such as is usually employed for this purpose and forms no part of the present invention. Hence I do not regard it as necessary to further illustrate or describe the same.

50 The table 12 and chuck 13 are suitably mounted in the main frame 14 by which the operative parts of the machine are supported. The relative position of the can body 1 and cover 3 after they are fed into the machine 55 is shown in dotted lines in Fig. 1.

The table 1 is mounted for vertical movement and after the can and cover have been fed into sealing position as shown by dotted lines Fig. 1, the table 12 is raised thereby 60 forcing the can up against the cover and at

the same time a follower 15 associated with the chuck 13 is lowered to meet the cover. The cover is then held between the follower 15 and the can and the table continues to move upwardly to carry the cover onto the 65 chuck as shown in Fig. 9 and to force the cover into the can mouth, the follower 15 retreating during this operation. A formed U-shaped sealing strip of the proper length is then fed into a position in which one end 70 thereof will embrace the sealing flanges 2 and 5 and the can is rotated and at the same time the flanges and sealing strip are pressed together through the co-operation of two 75 sealing members thereby sealing the can.

The table or can support 12 receives its 80 vertical motion above described through the medium of a cam 16 mounted on a cam shaft 17 that is journaled in the frame 14. This cam shaft is driven from a power shaft 18 through the medium of a pinion 19 on the power shaft which meshes with a gear 20 on the cam shaft.

The table or can support 12 is mounted on a shaft 21 which is suitably journaled in the frame 14 and is also vertically movable 85 therein. This shaft extends through a yoke 22, said shaft having a collar 23 thereon against which the yoke bears. The yoke 22 is connected by a link 24 to one end of a lever 25 which is pivoted at 26 to the frame 14 and carries at its free end a follower 27 which is adapted to be engaged by the cam 16.

The cam shaft 17 will make one rotation 90 for each cycle of operations and the cam 16 is so designed that during this rotation the table 12 will be raised at the proper time to carry the can up against the can cover and the latter against the chuck, and after the sealing operation has been completed will be lowered to allow the sealed can to be discharged.

95 In actual practice cans which are supposed to be of the same size often vary somewhat in height and in order to provide for such variation without injuring the can I propose to employ a yielding connection between the lever 25 and the yoke 22. Said yoke 22 has pins 28 rising therefrom which extend through a supplementary yoke 29 to which the link 24 is directly attached. Springs 30 encircle the pins 28 above the yoke 29 and are confined between said yoke and adjustable nuts 30 which are screwed on the pins. The force for lifting the table 12 is thus 100 transmitted through the springs 30 and when operating on a can which is somewhat taller than normal the springs will yield after the can engages the cover and during the last part of the movement of the lever 25 thus 105 preventing any injury to the can.

110 From the above brief description of the operation it will be remembered that the can and can cover are rotated while the sealing strip is being fed thereto and during the 115

sealing operation. This rotary movement of the can is secured by rotating both the table or can support 12 and the chuck 13, these two parts being rotated synchronously during the sealing operation.

For rotating the table 12 the shaft 21 has a gear 32 splined thereto which meshes with and is driven by a gear 33 on a vertical countershaft 34. This countershaft 34 is driven from the cam shaft 17 by a system of gearing which gives the shaft 34 an intermittent rotation. The cam shaft 17 is geared directly to and drives a vertical shaft 35 through suitable intermeshing gears 36 which may conveniently be spiral gears. This shaft 35 has fast thereto at its upper end a mutilated gear 37 and this mutilated gear co-operates with another mutilated gear 38 which is fast on the shaft 34.

The construction of the gears 37, 38 is such (see Fig. 11) that during each rotation of the gear 37 the gear 38 will be locked stationary through about three-quarters of the rotative movement of the shaft 35 and will be given a complete rotation during the other quarter of the rotative movement of said shaft.

The gears 36 are so proportioned that the shaft 35 will make one complete revolution for each revolution of the cam shaft 17 and by the system of gearing above described the shaft 34 will be given one revolution for each revolution of the cam shaft although the rotative movement of the shaft 34 will occur during the time that the cam shaft 17 or the shaft 35 is making about a quarter of its rotative movement.

The chuck 13 is also positively rotated as well as the table 12, these two elements rotating synchronously. The chuck 13 is rigid with a spindle or sleeve 39 (see Figs. 9 and 10) which in turn is rotatably mounted in suitable bearings 40 in the frame 14. This spindle has fast thereon a gear 41 which meshes with and is driven by a gear 42 rigid with the gear 38, (see Figs. 1 and 11). The gears 41, 42 have the same relation as the gears 32, 33 and, therefore, the chuck 13 and the table 12 rotate synchronously, but both sets of gears are so constructed that the table 12 and chuck 13 will rotate through slightly more than a complete revolution for each rotation of the shaft 34.

The two sealing members which operate on the sealing flanges of the can cover and can body and press them against the U-shaped sealing strip comprise a rotary-annular member 43 and a rotary sealing wheel 45. The annular member 43 is provided with an opening 49 of a size to freely permit the can to be inserted therethrough and at its upper portion it has the sealing portion 44 of reduced diameter and of a shape to fit into the groove 201 of the can, the upper face of the portion 44 forming a rest to support the sealing

flanges during the sealing operation as shown in Fig. 10.

The sealing wheel 45 is provided with a portion adapted to co-operate with the portion 44 of the annular member in effecting the seal and is also provided with a flange 46 adapted to engage the edge of the sealing strip and hold the latter in place while the sealing operation is being accomplished.

The sealing wheel is further provided with a guard rib 202 having a bevelled face and which is located beyond the sealing portion of the wheel. The purpose of this guard rib 202 will be presently described.

The sealing wheel 45 is positively driven and said wheel and sealing member 43 co-operate to seal the can as seen in Fig. 10.

This annular sealing member 43 is freely rotatable in one end 47 of a slide or carrier 48, which is slidable back and forth horizontally in ways in the frame 14. Normally the slide is so positioned that the opening 49 in the annular member 43 is directly over the can which is positioned on the can support 12 by one of the holders 9 of the turret 10, so that when the table or can support 12 is given its upward movement to assemble the can and the can cover said can cover and the upper end of the can will be carried upwardly through the opening 49 as shown in Fig. 9. After the can cover has been forced into the mouth of the can then the slide 48 is moved to the left Fig. 9 into the position shown in Fig. 10 thereby to bring the portion 44 of the annular member 43 underneath the flange 201 of the can body, and if the can is of the type having the groove 201 this portion 44 of the sealing member 43 will be carried into the groove as shown in Fig. 10 thereby forming a support for the sealing flange of the can body which is located within the confines thereof.

The sealing wheel 45 is mounted on this slide 48 so that it also has this lateral movement and by means of this movement said wheel and the portion 44 of the annular sealing member 43 are brought into position to act on the sealing flanges of the can and can cover. The sealing wheel 45 is capable of a vertical movement as well as its rotary movement and it is normally in its raised inoperative position shown in Fig. 9 so that there will be plenty of space between the sealing wheel and the portion 44 of the sealing member 43 to receive the unsealed flanges when the slide 48 is given its lateral movement. After the slide has been given its lateral movement then the sealing wheel is moved downwardly into operative position shown in Fig. 10 and is positively rotated. Before this is done, however, the U-shaped sealing strip is fed into position to embrace the sealing flanges 2 and 5. As this occurs the support 12 and chuck 13 will be given their turning movement and the sealing wheel 45 will

also be positively rotated, the combined operation serving to press the sealing flanges and sealing strip together and seal the can as will be obvious.

5 During the sealing operation the guard lip 202 rides against the corner of the can cover where the curb 4 and locking flange 7 meet and also rides on the face 203 of the chuck. In so doing said flange confines the metal of 10 the cover to the space between the rib 202 and the flange 46 and prevents any of this metal from flowing over onto the surface 203 by the pressure to which the sealing flanges are subjected during the sealing operation.

15 The slide 48 is given its operative movement through the medium of a cam 50 carried by the cam shaft 17, said cam acting against a follower on one end of a lever 51 pivoted to the frame at 52 and having its 20 upper end connected to a block 53 which in turn is connected to the slide 48 through a connection 54. Said slide 48 is provided with two side portions which are connected by a pin 55 and the connection 54 is mounted on said pin. The cam 50 will, of course, be properly timed to give the slide its forward movement at the proper point in the cycle of operations.

The sealing wheel 45 receives its vertical 30 movement from a cam 56 mounted on the cam shaft 17. As herein shown the sealing wheel is rotatable on a stud 57 which is mounted in a lever 58 pivoted on a pin 59 extending between the two sides of the slide 35 48, said lever 58 having the hub portion 60 through which the pin extends. At its free end the lever 58 carries a roll 61 which is acted upon by the cam 56 at the proper point in the cycle of operations.

40 When the parts are in the normal position shown in Fig. 1 with the slide 48 retracted the follower 61 will be out of the path of movement of the cam 56 but when the slide moves forwardly to the left to bring the parts 45 into the position shown in Fig. 10 then the follower 61 is brought to a position to be engaged by the cam 56 which will swing the right hand end of the lever 58 upwardly and thereby moving the sealing wheel 45 downwardly at the proper point in the cycle of operations.

I have stated above that the sealing wheel 45 was positively driven and for this purpose I have provided the following mechanism. This sealing wheel has a gear 62 rigid therewith, which gear meshes with a gear 63 on a countershaft 64. Said shaft 64 is provided with a sprocket wheel 65 over which operates a sprocket 66, said sprocket being 50 driven in turn by a sprocket wheel 67 mounted on a shaft 69 carried in suitable bearings 70. This shaft 69 is provided with a bevelled gear 71 meshing with a bevelled gear 72 and the gear 72 has rigid therewith a pinion 73 which 55 meshes with and is driven by a gear 74 that

is fast on the sleeve 39. The power for driving the sealing wheel is, therefore, taken from the sleeve 39 which carries the chuck 13.

Inasmuch as the gear 62 has a vertical rocking motion about the stud 59 it will be necessary to back off the teeth of said gear slightly so that the teeth of the gears 62, 63 will not bind during such rocking motion. 70

Another feature of my invention relates to a can sealing machine constructed to perform the sealing operation with separate formed sealing strips U-shape in cross section. For this purpose I have provided a strip-receiving magazine adapted to hold a plurality of separate formed sealing strips U-shape in 75 cross section and each of the proper length to seal a can and have also provided means for automatically feeding the strips one by one from the magazine to the successive cans as they come into sealing position. 80

The strip magazine is shown as in the form of two pairs of guiding bars or members 75 which are carried by two side plates 76. The bars of each pair 75 are spaced apart slightly to form between them a space 77 of 90 a size to receive one end of each of the formed strips. The plates or side pieces 76 are spaced apart a distance equal to the length of the individual strips so that when the strips 6 are in the magazine they will be confined between the sides 76 and the ends thereof will be in the guideways 77. 95

Means are provided for automatically feeding the strips into the guideways 77 and for this purpose I have provided a feed drum 100 78 which is formed on its periphery with a plurality of blades 79 each having a V-shaped edge 80 of a size to fit into the V of the sealing strips 6. Associated with the feed drum 78 is a hopper 81 into which the strips 105 may be deposited in a miscellaneous manner as shown in Fig. 5.

The feed drum is rotated anti-clockwise as viewed in Fig. 5 and the V-shaped edges 80 are on the forward or leading sides of the blades 79. As this drum rotates and each blade enters the lower end of the hopper the strips in the hopper will be agitated or stirred up and as each blade passes through the hopper it will pick up a strip as shown in Fig. 5. In 110 said figure only a few strips 6 have been illustrated in the hopper but it will be understood that in practical operation the hopper will be substantially full of strips so that before each blade emerges from the upper end of the hopper it will have picked up a strip on its V-shaped edge 80. 115

One of the guide bars 75 of each pair is provided with a curved extension 82 under which the blades 79 pass as shown in Fig. 3. Each 120 of these blades will thus carry its strip around underneath the extension 82 and with the ends of the strip in alignment with the guideways 77. 125

Means are provided for doffing the strips 130

from the blades 79 and delivering them to the guideways 77. This doffer is herein shown as in the form of a rotatable shaft 83 which carries pins 84 that are adapted to engage the strips as the shaft rotates. The shaft, as shown in Fig. 3 is given a clockwise rotation, its rotative movement being so timed relative to that of the drum 78 that as each strip reaches the upper end of the guideway 77 it will be engaged by the pins 84 and will be knocked off from the blade 79 and into the guideway.

The drum 78 is shown as fast on a shaft 85 which is journaled in suitable bearings in the frame and is provided with a driving pulley 86 by which it may be operated. Said shaft carries a gear 87 which meshes with a pinion 88 on the shaft 83 so that the shaft 83 and the drum 78 are driven from the same source of power. With this mechanism, therefore, the individual strips will be picked up on the edges 80 of the bars 79 and deposited in the runways 77 by the rotating pins 84. These blades deliver the strips to the guideways 77 in the proper position to be fed to the can.

89 is a clearer which has for its purpose to clear the bars 70 of any extra strips which may be caught thereon. If perchance more than one strip is being carried up by any bar the extra strip will be scraped off by the clearer 89 so that as the bars advance toward the top of the guideways 77 each bar will carry a single strip only.

At the lower end of the magazine is a plate 94 which is secured to a supporting bar 95 and which has at its front edge a groove 96 of a size to receive a formed sealing strip 6 as shown in Fig. 7. This groove 96 is in line with the guideways 77 of the magazine so that the bottom strip in the magazine will lie in the groove 96 in the manner shown in Fig. 7.

Means are provided for feeding the bottom sealing strip of the stack of strips out of the magazine into position to be sealed into a can. This operation is accomplished through the medium of a pick-off or feeding member 90 which is reciprocable on a suitable guiding member 91 forming part of the frame. The pick-off or feeding member 90 is formed at one end and along one edge with a groove 92 shaped to receive one end of the bottom strip 6 and it is also provided with an inclined finger or projection 93 which is adapted to engage the end of the strip and enter slightly between the sides thereof as shown in Fig. 6.

The forward movement of the pick-off member 90 will thus push the bottom strip out from the magazine and means are provided whereby such strip when so pushed will be guided into position so that one end thereof will embrace the sealing flanges 2 and 5 of the can body and cover respectively.

The groove 96 in the member 94 constitutes a portion of this guiding means and this groove co-operates with a guiding fin 97 which fits the hollow of the sealing strip 6 as shown in Fig. 8 and which is situated between the delivery end of the magazine and the sealing position of the can. Hence as the sealing strip is moved forwardly by the pick-off 90, or to the right in Fig. 6, said strip will be forced along the groove 96 and over the fin 97 and these two elements will hold the strip in proper position so that it will be correctly guided onto the flanges 2 and 5.

In Fig. 6 the strip-feeding member 90 is shown as partially advanced, that is, the strip has been pushed partially out of the magazine. The normal position of the strip when in the magazine and the normal position of the pusher 90 is shown in dotted lines Fig. 6. At the appropriate time in the cycle of operations the pusher 90 is given a forward movement and during such movement it engages the strip at the bottom of the magazine and pushes the same longitudinally along the guideway 96 and also over the fin 97, the strip being guided by these two parts during its movement. The movement of the pusher or feeding member 90 is sufficient to deliver the end of the strip 6 into position to embrace the flanges 2 and 5 of the can and can cover and as soon as the strip has reached this position the can is rotated and the sealing members are set in operation to seal the can. As the can and the sealing members rotate the sealing strip will be drawn from the magazine and laid into position as the can is sealed.

The movement of the member 90 is controlled by means of a cam 98 on the shaft 35, see Figs. 1 and 2. Said cam co-operates with a lever 99 pivoted to the frame at 100 and connected by a link 101 to one end of the feed member 90 as shown at 102. The feed member 90 is acted on by a pulling spring 103 which co-operates with the cam 98 in operating said feed member. The cam gives the feed member its retractive movement while the spring 103 gives its forward feeding movement.

When the feed member 90 has been fully retracted the finger 93 thereof will be carried beyond the limits of the magazine and the strips in the magazine will move downwardly so that the bottom strip will occupy the groove 96 in the guide member 94. When the pusher member moves forwardly the finger 93 will pick up the bottom strip 6 and deliver it from the magazine into position to embrace the sealing flanges 2 and 5 of the can and into position to be acted on by the sealing members 43, 45.

In order that the pick-off 90 may operate properly it is, of course, necessary that there should always be a sealing strip 6 at the bottom end of the magazine and in order to ensure that this condition will always obtain I

have provided means for feeding the strips downwardly in the raceway. Such means is in the form of two feeding rolls 205 (see Figs. 2 and 3) which are mounted on a shaft 206 that is carried in two arms 207 that are loosely hung on the shaft 83. The shaft 206 has an upstanding arm 208 which is connected by two springs 209 with the end of an actuating member 210. This member 210 is provided with a slot 212 in which is received a pin 211 carried by the upstanding arm 208, this pin and slot serving to guide the actuating member and hold it in position. The member 210 is given a reciprocating motion and at each movement toward the right Fig. 3 it will give the feed wheels 205 a partial turning movement. These feed wheels rest against the formed sealing strips 6 and such turning movement of the wheels will tend to feed the strips downwardly thereby to maintain a strip at the bottom of the magazine in the groove 96.

The actuating member 210 receives its reciprocation from a crank pin 213 to which it is connected and which is located at the upper end of a shaft 214, the latter being driven from the cam shaft 217. For this purpose said cam shaft has fast thereon a gear 218 meshing with a gear 219 and the latter gear has fast thereto a bevelled gear 220 which meshes with a bevelled gear 221 on the lower end of the shaft 214.

I have provided herein a safety attachment which will lock the feed member 90 from movement so long as no cans are being delivered to the machine but which is rendered inoperative while cans are being properly delivered. This safety device is in the form of a latch member 104 which is adapted to engage a shoulder 105 on the slide 90, (see Figs. 2 and 4), and which is carried by a swinging arm 106 pivoted to the frame at 107. The position of the latch is controlled by an inclined cam portion 108 of a can-actuated slide 109 which is guided in suitable guideways 110 and is provided at one end with a shoe portion 111 situated to be engaged by a can body 1 as it is carried around by the turret 10 into sealing position, (see Fig. 4). The engagement of any can body with the shoe 111 will force the slide 109 to the left Fig. 4 against the action of the spring 112.

The inclined cam portion 108 of the slide operates between two pins 113 carried by the swinging arm 6 and hence as the slide 109 is moved to the left Fig. 4 the inclined portion 108 thereof will co-operate with the pins 113 to swing the arm 106 downwardly thereby withdrawing the latch member 104 from the shoulder 105 and releasing the feed member 90. Hence each time that a can is fed into sealing position the latch 104 which holds the feed member in its rearward position will be released and the feed member will be given a forward movement by the spring 103 there-

by feeding the strip into position to be sealed into the can. As soon as the feed member has performed its feeding function the cam 98 operates to restore the feed member to its rearward position in which position it is automatically locked by the latch 104.

It will be understood that after the can passes off from the shoe 111 the spring 112 will tend to restore the slide 109 to the position shown in Fig. 4 and thereby restore the latch to its operative position but so long as the feed member is in its forward position the latch will engage the under side of the feed member during its return movement until the feed member has been sufficiently retracted by the cam 98 to carry the shoulder 105 beyond the latch 104. When this occurs the latch will immediately move into place and thus lock the feed member from forward movement until the latch is again released by the engagement of a can with the shoe 111.

The parts are shown in Figs. 2 and 4 with the feed member locked.

With this device, therefore, there will be no feed of a strip 6 unless a can is being presented into position to be sealed.

Another feature of the invention relates to novel means for doffing the sealed can from the chuck member 13 after the sealing operation has been completed. It will be remembered that during the sealing of the can the can support 12 is in raised position and the can is firmly retained between the can support and the chuck 13 which at this time fits into the cover 3.

When the sealing operation has been completed the table or platform 12 is lowered and at this time the follower 15, which normally is received within a recess 114 formed in the chuck member 13, is forced downwardly to push the can off from the chuck member. This follower or can-doffer 15, as it might be called, is fast on a plunger or rod 115 which is movable vertically through the spindle 39. At its upper end the rod is swivelled in a collar 116, said collar and rod being turnable relative to each other but capable of having no longitudinal movement relative to each other.

This collar 116 is connected by a link 117 to one end of a lever 118 pivoted at 119 to a bracket 120 carried by the frame 14. The free end of the lever 118 has a roll 121 thereon adapted to be engaged by cam projections 122, 123 formed on a disk 124 which is fast on the shaft 35. These cam projections are so arranged that just after the sealing operation has been completed the cam projection 122 will engage the roll 121 and rock the lever 118 thereby giving the can-doffing member 15 a quick downward movement which will doff the can from the chuck. A return spring 125 connected to the lever 118 operates to return the doffer to its normal position. The other cam projection 123 actuates the member 15

just at the time that the platform 12 is being elevated. As the platform 12 rises to bring the can body into engagement with the can cover the cam member 123 will force the follower 15 downwardly below the chuck into a position to meet or engage the can cover, this occurring just about the time that the can has been brought up to the cover by the rising movement of the table 12. Hence at this time the can and cover will be held between the member 15 and the table and as the table continues its upward movement to bring the cover onto the chuck the follower 15 will retreat, the cam 123 having performed its function.

I have stated above that the turntable 10 was given an intermittent turning movement. This is accomplished through the following mechanism.

The shaft 35 has fast thereon a gear 126 which meshes with a second gear 127 rotatably mounted on a stud 128. The gear 128 has a crank pin 129 to which is connected a link 130 leading to a segmental gear 131.

This gear 131 is fast to a sleeve 132 loosely mounted on the shaft 133 of the turret 10. This sleeve 132 has splined thereon a clutch member 134 which co-operates with a clutch member 135 that is fast on the shaft 133. The

clutch member 134 is capable of vertical sliding movement on the sleeve 132. The connections for driving the segmental gear 131 are such that the rotation of the gear 127 will simply oscillate the gear 131. The clutch

members 134, 135 constitute in effect a ratchet device by which the shaft 133 will be ratcheted forward with a step-by-step movement, such movement, of course, being in timed relation with the other movements of the machine.

The gear 131 meshes with a gear 136 on a shaft 137 by which the pick-off or feed device for the can covers is operated. This pick-off or feed device, however, is not herein illustrated as it forms no part of the present invention.

While I have herein illustrated the invention as embodied in a machine which applies a U-shaped sealing strip to a particular type of can yet it will be understood that the invention is not limited in its application to a can having just the shape shown but is adaptable generally for use in sealing a can where the sealing strip has a general U shape and is adapted to embrace a sealing flange on either the cover or the can body and to be clamped against the other part. Hence it will be understood that various changes can be made in the constructional details of the device without in any way departing from the invention.

I claim:

1. In a machine for sealing a can by means of a longitudinally-grooved sealing strip, the combination with means to assemble in sealing relation a can body and a cover therefor

one of which has a flange to be embraced by the sealing strip and the other of which has a portion against which the sealing strip is clamped, of automatic means to feed a formed sealing strip of a length to seal the can into position to embrace said flange, and means to clamp the sealing strip to said flange and said portion. 70

2. In a machine for sealing a can, the combination with a can support, of means to present can bodies successively to said support, means to assemble a can cover having a sealing flange in sealing relation with each can body, automatic means to feed a formed sealing strip of a length to seal the can into 80 position to embrace said sealing flange, and means to clamp the strip to said flange and to the can body thereby to seal the can. 75

3. In a can-sealing machine, the combination with a can support, of means to present can bodies successively to said support, means to assemble a can cover having a sealing flange with each can body, automatic means to feed a formed sealing strip of a length to seal the can into position to embrace said sealing flange and to engage the can body, and means acting on the sealing flange progressively to clamp it to the sealing flange and can body thereby to seal the can. 85 90

4. In a machine for sealing a can in which the can body and cover are provided with sealing flanges that are embraced by a sealing strip U-shape in cross-section, the combination with means to assemble in sealing relation a can body and cover each having a sealing flange, of automatic means to feed a formed sealing strip of a length to seal the can into position to embrace said flanges, and means to press the sealing strip and flanges together to seal the can. 95 100

5. In a can-sealing machine of the class described, the combination with a can support, of means to present can bodies successively to said support, means to assemble a can cover in sealing relation with each can body, automatic means to feed a formed sealing strip of a length to seal the can into position to embrace the sealing flanges of the can body and cover of each can, and means to press the sealing strip and said flanges together thereby to seal the can. 105 110 115

6. In a can-sealing machine of the class described, the combination with means to assemble in sealing relation a can body and a cover each having a sealing flanges, a magazine containing a plurality of separate formed sealing strips U-shape in cross section, automatic means to feed a strip from the magazine into position to embrace the sealing flanges of the can and cover, and means to press said flanges and sealing strip together thereby to seal the can. 120 125

7. In a can-sealing machine of the class described, the combination with means to assemble in sealing relation a can body and a

cover each having a sealing flange, a magazine containing separate formed sealing strips U-shape in cross section, means to feed a sealing strip from the magazine and to 5 guide said strip as it is fed into position to embrace the sealing flanges of the can and cover, and means to press the sealing strip and flanges together thereby to seal the can.

8. In a can-sealing machine of the class 10 described, the combination with means to support in sealing relation a can body and can cover each having a sealing flange, of a magazine to contain separate sealing strips U-shape in cross section, means to automatically supply sealing strips to said magazine, 15 means to feed a sealing strip from said magazine into position to embrace the flanges of the can and cover, and means to press said flanges and sealing strip together thereby 20 to seal the can.

9. In a can-sealing machine, the combination with means to support in sealing relation a can body and can cover each having a sealing flange, of a magazine to contain 25 individual sealing strips U-shape in cross section, automatic means to deliver said sealing strips to said magazine with each sealing strip in a predetermined position, means to feed strips singly from said magazine 30 into position to embrace the sealing flanges of a can supported on the can support, and means to press the flanges and sealing strip together thereby to seal the can.

10. In a machine for sealing a can in which 35 the can body and can cover are each provided with sealing flanges that are embraced by a sealing strip U-shape in cross section, the combination with a can support, of a freely-rotatable annular sealing member surrounding the can on the support and on the upper edge of which the sealing flange of the can rests, of a magazine containing separate sealing strips U-shape in cross section, automatic means to feed a strip from said magazine into 45 position to embrace the flanges of the can and cover, means to rotate the can, and a sealing wheel co-operating with the annular sealing member to press said flanges and sealing strip together as the can is rotated.

11. In a can-sealing machine, the combination with a can support, of means to present to said support successive can bodies each having a lateral sealing flange, means to assemble in sealing relation with each can body 55 a can cover also having a sealing flange, automatic means to feed a formed sealing strip of a length to seal the can into a position to embrace the sealing flanges of the assembled can body and cover, means to press the sealing strip and flanges together thereby to seal the can, and means to render the strip-feeding means inoperative upon failure of a can to be presented to the can support.

12. In a can-sealing machine, the combination with a can support, of means to present

successively to said support can bodies each having a sealing flange, means to assemble in sealing relation with each can body a can cover also having a sealing flange, normally inoperative means to feed a formed sealing strip into position to embrace the sealing flanges of the can body and cover of each can when supported on the can support, and means controlled by the can bodies as they are carried into sealing position to render the strip-feeding means operative. 70

13. In a can-sealing machine, the combination with a can support, of means to present can bodies successively to said support, each body having a sealing flange, means to assemble a can cover in sealing relation with each can body, each cover having a sealing flange, spring-actuated means to feed a sealing strip U-shape in cross section into position to embrace the sealing flanges of the assembled can body and cover, a latch to hold said feeding means inoperative, and means actuated by each can body as it is delivered to the can support to release the latch. 80

14. In a can-sealing machine, the combination with a can support, of means to present can bodies successively to said support, each body having a sealing flange, means to assemble a can cover in sealing relation with each can body when on the support, which 95 cover also has a sealing flange, a magazine containing a plurality of separate formed sealing strips U-shape in cross section, means for feeding the strips separately from the magazine into position to embrace the sealing flanges of the can and cover on the can support, and means to render the strip-feeding means inoperative when the supply of cans to the can support fails. 100

15. In a machine for sealing a can in which the can body has a sealing flange and an annular groove immediately below the sealing flange, the combination with an annular rotatable sealing member having an opening slightly larger than the can body and an annular rib of a shape to fit the groove, of means to support an assembled can and cover in a position in which said rib fits into said groove at one side of the can with the sealing flanges resting on the rib, means to rotate the can, 110 means to feed a sealing strip U-shape in cross section into position to embrace said flanges, and a sealing wheel cooperating with said sealing member for pressing the flanges and sealing strip together thereby to seal the can. 115

16. In a can-sealing machine for sealing a can in which the can body has an annular groove at its upper end and a sealing flange forming the upper wall of said groove and in which the can cover has a sealing flange overlying that of the can body, the combination with a rotatable annular sealing member having a reduced upper end of a shape to fit the groove of the can, of means to support an assembled can and cover with the reduced 125 130

portion of the sealing member fitting the groove of the can at one side and forming at said point a rest for the sealing flanges, and a sealing wheel co-operating with the 5 sealing member for pressing the flanges together.

17. In a can-sealing machine for sealing a can in which the can body has an annular groove at its upper end and a sealing flange 10 forming the upper wall of said groove and in which the can cover has a sealing flange overlying that of the can body, the combination with a rotatable annular sealing member having a reduced upper end of a shape to 15 fit the groove of the can, of means to support an assembled can and cover with the reduced portion of the sealing member fitting the groove of the can at one side and forming at said point a rest for the sealing flanges, 20 means to deliver to the can a U-shaped sealing strip which embraces said sealing flanges, and a rotatable sealing wheel co-operating with the sealing member to press said flanges and sealing strip together thereby to seal the 25 can.

18. In a can-sealing machine for sealing a can in which the can body has an annular groove at its upper end and a sealing flange forming the upper wall of said groove and 30 in which the can cover has a sealing flange overlying that of the can body, the combination with a rotatable annular sealing member having a reduced upper end of a shape to fit the groove of the can, of means to support an assembled can and cover with the 35 reduced portion of the sealing member fitting the groove of the can at one side and forming at said point a rest for the sealing flanges, means to deliver to the can a U-shaped sealing strip which embraces said sealing flanges, 40 a rotatable sealing wheel co-operating with the sealing member to press said flanges and sealing strip together thereby to seal the can, means to rotate the can while being sealed, 45 and means to rotate the sealing wheel.

In testimony whereof, I have signed my name to this specification.

HARRY SEBELL.
